ROTARY TOOTHBRUSH

Melvin C. Grout and Marion E. Frost,
Springfield, Ohio

Application July 15, 1940, Serial No. 345,638

1 Claim. (Cl. 15—28)

The present invention relates to improvements in rotary toothbrushes.

An important object of the invention resides in the provision of a rotary toothbrush embodying a water motor whereby the brush may be driven from an ordinary water tap or faucet.

Another object of the invention is to provide a rotary toothbrush including a casing and housing of novel formation, the casing serving as a handle for the toothbrush and the housing confining the water motor with a shaft extending through the casing and attached by novel means on one end to the water motor and the other end thereof removably supporting the brush element.

The invention also consists in certain other features of construction and in the combination and arrangement of the several parts, to be hereinafter fully described, illustrated in the accompanying drawing and specifically pointed out in the appended claim.

In describing our invention in detail, reference will be had to the accompanying drawing wherein like characters denote like or corresponding parts throughout the several views, and in which:

Figure 1 is a side elevational view of a rotary toothbrush in accordance with the present invention.

Figure 2 is a horizontal sectional view thereof taken substantially on line 2—2 of Figure 1.

Figure 3 is a detail sectional view taken substantially on line 3—3 of Figure 2.

Figure 4 is a vertical sectional view taken substantially on line 4—4 of Figure 3.

Figure 5 is a horizontal sectional view taken substantially on line 5—5 of Figure 4 with the water motor removed from the housing.

Referring to the drawing for a more detailed description thereof, the rotary toothbrush embodying the features of the present invention is generally designated by the reference numeral 8 and comprises a substantially cylindrical-shaped casing 9 preferably formed of a plastic material. The interior of the casing 9 is formed with a longitudinally disposed passage 10 for housing a shaft 11, said shaft being preferably fabricated of bronze or similar material. The shaft 11 is journaled in bushings 12 and 13 secured in each end of the longitudinal passage 10. The bushings 13 surrounding the shaft adjacent the water motor are separated by means of a resilient packing ring 14.

The housing for the motor is generally designated by the reference numeral 15 and likewise

is preferably formed of a plastic material. The housing 15 is frictionally held on a collar portion 16 forming a part of the casing 9 and by referring more particularly to Figure 2 of the drawing, it will be observed that the end of the casing adjacent the housing 15 is flared outwardly as indicated at 17 and that the collar 16 is a reduced portion of the flared end 17. The interior of the housing 15 is hollow as indicated at 18 for confining the water motor 19, the diameter of the opening 18 being substantially equal to the diameter of the collar 16. The water motor 19 is arranged to revolve within the housing 15 and is keyed to the shaft 11. As more clearly shown in Figures 3 and 4 of the drawing, the end 20 of the shaft 11 is flattened and tapers outwardly so as to be securely held within the opening 21 formed centrally of the water motor 19 which opening corresponds in shape and size to the flattened end 20. The water motor 19 comprises a disk-shaped wheel 22 having a series of vanes 23 integral with and projecting from the periphery thereof. The wheel 22 is prevented from contact with the end of the collar 16 and the end wall 24 of the opening 18 by means of the bushing 13 and pin 25. The pin 25 forms a part of the housing 15 and extends a slight distance within the opening 18 while the outermost bushing 13 also extends a slight distance within the opening 18. The pin 25 bears on one side of the wheel 22 while the bushing 13 bears on the opposite side of said wheel thus maintaining the wheel properly centered within the opening to prevent axial movement thereof when revolving.

The housing 15 is adapted to be attached to any ordinary water tap or faucet for supplying water to the interior of the housing to rotate the wheel 22. Inlet and outlet openings 26 and 27 respectively, are formed in the bottom wall of the housing 15, the inlet opening being internally threaded for the attachment of a fitting 28, said fitting receiving one end of a hose or the like 29, the other end of said hose being attached to the water tap or faucet. A passageway 30 communicates with the inlet opening 26, said passageway communicating with the opening 32 whereby the passage of water therethrough will contact the vanes 23 for revolving the wheel 22 and its shaft 11. The water is discharged from the housing through the passageway 31 which communicates with the outlet opening 27. It will be observed in Figure 4 of the drawing that the end of the passageway which communicates with the opening 18 is reduced in diameter as

indicated at 32 for restricting the stream of water being discharged against the vanes 23.

The outer end of the shaft 11 is formed with a threaded opening 33 for receiving the threaded end 34 of a toothbrush 35 whereby interchanging of the brushes can be readily accomplished. It is, of course, to be understood that brushes other than toothbrushes can be attached to the shaft 11.

It is believed that the mode of operation of the device will be readily understood, and it will be seen that when the device is in use the brush 35 will be revolved at a desired rate of speed thus adapting it to exert a proper cleansing action. The speed of rotation of the brush can be adjusted by increasing or decreasing the pressure of water supplied to the motor 19 from the tap or faucet. The manifold advantages of the invention will be evident from the foregoing description when considered with the accompanying drawing.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of

the drawing nor to the precise construction described and, therefore, such changes and modifications may be made therein as do not affect the spirit of the invention nor exceed the scope 5 thereof as expressed in the appended claim.

What is claimed is:

In a device of the character described, a casing having a longitudinal bore, the interior of the casing being enlarged at each end portion to 10 provide counter-bore sections of increased diameter, a bushing sleeve fitted in the counter-bore in the outer portion of the casing, a pair of relatively short bushing sleeves mounted in the counter-bore in the opposite end portion of the 15 casing and disposed in longitudinally spaced relation, a packing ring fitted in the said counter-bore between the said spaced bushing sleeves, a housing at one end of the said casing forming a chamber therein, the said housing having inlet and outlet passages, a shaft rotatably extended through the bore of the casing and journaled in the bushing sleeves mounted therein, a brush member connected to the outer end of the said shaft, and a fluid operated wheel fixed on the 20 opposite end of the shaft and rotatably mounted in the chamber of the housing.
